CLAIMDESCRIPTION

FIG. 1 is a front perspective view of a combined kettle and side tables for a barbecue grill, showing our new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof;

FIG. 7 is a bottom plan view thereof; and,

FIG. 8 is a bottom plan view thereof without environmental broken lines.

The broken line showing of environment is for illustrative purposes only and forms no part of the claimed design.

The ornamental design for a combined kettle and side tables for a barbecue grill, as shown and described.
